UNITED STATES PATENT OFFICE.

ABRAM O. HANCOCK, OF RICHMOND, VIRGINIA.

HEADREST.

Application filed February 16, 1922. Serial No. 537,055.

To all whom it may concern:

Be it known that I, ABRAM O. HANCOCK, a citizen of the United States, and a resident of Richmond, in the county of Henrico and State of Virginia, have invented certain new and useful Improvements in Headrests, of which the following is a specification.

This invention relates to a head rest.

10 The object of the invention is to provide a head rest which may be secured to the body of a person and serve to support the person's head whether in a seated or reclining position.

15 It is also an object of the invention that the head rest be adjustable to suit persons of different stature.

20 It is a further object of the invention that the device be foldable into a compact bundle so that the same may be easily transported from place to place.

25 It is also within the scope of the invention that the head rest be exceedingly simple in construction and inexpensive to manufacture.

Other objects will hereinafter appear.

The invention is illustrated by way of example in the accompanying drawings, in which:—

30 Figure 1 is a perspective view illustrating the application of the invention.

Figure 2 is an enlarged perspective view of the device showing the same when fully assembled.

35 Figure 3 is a detailed sectional view taken substantially on the line 3—3 of Figure 2.

Figure 4 is a detailed perspective view of the belt used with the head rest and illustrating the manner in which the supporting arms are connected to said belt.

40 Figure 5 is a view in side elevation showing another application of the invention.

Figure 6 is a rear view of the head rest shown in Figure 5.

45 Figure 7 is a detail perspective view of the supporting legs.

Figure 8 is a transverse sectional view taken on lines 8—8 of Figure 6.

Figure 9 is a rear view of a modified 50 form of head rest.

Figure 10 is a transverse sectional view on line 10—10 of Figure 7.

Referring to the drawings generally, A indicates a pair of supporting arms and H 55 a head rest. Each arm consists in the telescopic tubular sections 10, 11 and 12. The

sections are preferably arranged so that the movement of one section within the other is limited and also that said sections may be detached from one another when desired.

Referring particularly to Figures 1 to 4 inclusive the head rest H consists in a plate 9 preferably of light sheet metal, and having its edge formed with a bead as at 13, Figure 3, in order to reinforce the plate. The head plate 9 is longitudinally curved as shown and its surface formed to correspond as near as possible to the curvature of the back of a person's head.

Adjacent each end of the head plate there is secured a strap 14 by the means of rivets or the like as shown. Each strap has a portion extending from the head plate H, which portion is pivotally connected with the upper end of the associated tubular member 10 by the means of a bolt or the like as at 15. The strap 14, in each instance, extends from the head plate H a sufficient distance to permit the tubular members 10 to be folded inwardly toward each other.

For each tubular member 10 there is provided a pad 15' which is preferably of the shape shown and may be made of sheet iron or other metal. Each pad 15' is formed with a pair of eyes 16 and adapted for receiving a tubular member 10. The pads 15' may be slid longitudinally of the tubular members 10.

The lower end of each tubular member 12 is slightly enlarged as at 17 and this enlarged portion is provided with an elongated slot 18. A belt B is provided which is adapted to extend about the waist of a person and which is provided with a buckle 19 for adjustably securing its ends together. The belt is also provided with a strap 20 which has its ends secured to the belt by buttons as at 21. One end of the strap 20 may be provided with a number of button holes, as shown in Figure 4, in order that the same may be adjusted when adjusting the belt B.

For the head plate H there is provided a cushion generally indicated by the reference character C. This cushion may consist in a suitable casing 22 in which there is inserted suitable stuffing as at 23, Figure 3. The casing may be adapted to slip about the head plate H and entirely cover the same and then properly stitched or sewed to hold the same against removal. It is of

course to be understood that the cushion C need not be of the type shown but may be a pneumatic cushion if desired.

In Figure 1 there is illustrated a use of the present device and in which there is shown a person seated upon a chair C'. The belt B is secured about the person's waist and the arms A rest upon his shoulders, while the cushion C is disposed at a point at the back of the person's head and in position for supporting the same. The pads 15 should be placed upon the shoulders of the user so that the pressure upon the arms A will be imposed upon his shoulders. The pads 15 may be adjusted to suit the desires of the user of the head rest.

The device as before stated is easy to fold into a compact bundle for transporting. When folding the device the sections 11 and 12 may be withdrawn from each other and also from the sections 10 and then the sections 10 may be folded inwardly. The sections 11 and 12 may now be arranged longitudinally of the head plate 40 and the whole secured together in a small and compact bundle. If desired the belt B may be utilized for securing the different parts together to form a compact bundle.

It may be here mentioned that the arm A are preferably made of tubular sections in order to retain the desired likeness and supporting strength.

It should also be pointed out that when the device is positioned upon a person, as shown in Figure 1, the head support or rest cannot move from its supporting position, the same being supported by both the arms A and the upper portions of the shoulders of the wearer. This is important for the reason that it prevents displacement of the head rest irrespective of the position the person may assume.

Referring to Figures 5, 6, 7 and 8 the head H and supporting legs A are of the construction described and shown in Figures 1 to 4 inclusive and like reference numerals indicate similar parts, or elements. In this instance the head plate 10 is provided with a support or rest generally indicated by the reference character S. This support consists in a shaft portion 24 from which then extends the two legs 25 one adjacent each end thereof. The legs are preferably braced by the V-shaped strut 26. Upon the head plate 10 is secured two supporting clips 28, each clip being received adjacent its end by a screw or nut as shown and the free end of clips adapted to permit the ends of shaft 24 to be sprung therebeneath and so turnably held. The plate 10 in this instance is formed with a bead 13' which is turned forwardly in contra-distinction to the bead 13 on the same plate shown in Figures 1 to 4 inclusive.

In Figure 5 the head rest is shown when

serving to support a person's head when working beneath a motor vehicle. In this figure M indicates generally a motor vehicle. A man is shown beneath the motor vehicle and reclining upon his back. The arms A are secured by belt B and the pads 15 rest upon the man's shoulders and support the head rest H in proper position which serves to support the man's head. In this instance the supporting member S is swung to a substantially vertical position with relation to the head rest H and further supports the same.

Referring to Figures 9 and 10 the head plate 10 in this instance has secured upon the rear face thereof a strap 30, said strap extending longitudinally of the plate and being secured by the means of rivets or the like. Intermediate the ends of the strap there is formed an extension 31 which is in the form of a short curved bar as best shown in Figure 10. The extension 31 has its sides serrated as at 32, and the bar is further provided with a longitudinally extending slot as indicated at 33, Figure 10.

In the present form of my invention each arm section 15 is formed at its free end with an eye 34 to which there is pivotally connected the one end of an arm 35. The arm 35, in each instance, is curved as shown in Figure 4 and its free end portion 36 bent at substantially right angles thereto. The free end portion 36, in each instance, has its inner end serrated as shown in Figure 9. The free end portions 36 of the arms 35 are connected together by a suitable bolt 37, said bolt being preferably provided with a wing nut 38. The bolt 37 also extends through the slot 33 in the extension 31 and is adapted to adjustably hold said extension between the arms 35 in an obvious manner.

The purpose of making the distance between the head rest H and arms A adjustable as described for Figures 9 and 10 is to make the device adapted to be suited to persons whose necks are of different length.

The head plate 10 shown in Figure 9 is also provided with a pair of spring clips 27 whereby the supporting member S shown in Figure 7 may be turnably supported.

While I have shown and described the different forms of my invention, I wish it to be understood that I am aware of the fact that the construction, combination and arrangement of parts may be changed by those skilled in the art without departing from the spirit of the invention as indicated by the appended claims.

I claim:

1. A head rest of the character described, comprising a pair of arms, each consisting in a plurality of telescopic tubular sections, means whereby said arms may be secured to the body of a person at the waistline thereof, said arms being adapted to extend upwardly

and beyond the shoulders of a person, a head rest supported between the upper ends of said arms and adapted to be positioned at the rear of the user's head to serve as a support therefor, and a pad slidable upon each arm adapted to be adjusted to be brought to a point upon the arm where the greatest pressure is exerted for supporting the head rest upon the shoulders of the user.

- 5 10 2. In a device of the character described, an elongated head rest, a projection adjacent each end of the head rest and occurring upon the inner edge thereof, an extensible arm pivotally connected at its one end to each projection, each extensible arm comprising a plurality of tubular telescopic sections, the innermost section of each arm being adapted to receive the other sections and then be folded inwardly upon the associated 15 20 edge of the head rest, and means carried by the free ends of said arms whereby the same may be attached about a person's body.
3. A device of the character described, comprising in combination, a head rest consisting in a plate member with padding upon 25

one side thereof, a projection adjacent each end of the plate and extending from the inner edge thereof, an arm pivotally connected at its one end to each extension and each arm comprising a plurality of telescopic tubular sections, the innermost section in each instance being adapted to receive the other sections and then folded inwardly and upon the associated edge of the head rest.

- 30 35 40 45 4. A device of the character described, comprising in combination, a head rest consisting in a plate member with padding upon one side thereof, a projection adjacent each end of the plate and extending from the inner edge thereof, an arm pivotally connected at its one end to each extension and each arm comprising a plurality of telescopic tubular sections, the innermost section in each instance being adapted to receive the other sections and then folded inwardly and upon the associated edge of the head rest, and a pad slidable longitudinally of the innermost tubular section of each arm for the purpose described.

ABRAM O. HANCOCK.
